UNITED STATES PATENT OFFICE.

AUGUSTE EDOUARD PINSON, OF OUTREMONT, QUEBEC, CANADA.

SCRUBBING GLOVE.

1,403,817.

Specification of Letters Patent. Patented Jan. 17, 1922.

Application filed September 20, 1920. Serial No. 411,617.

(GRANTED UNDER THE PROVISIONS OF THE ACT OF MARCH 3, 1921, 41 STAT. L., 1313.)

To all whom it may concern:

Be it known that I, AUGUSTE EDOUARD PINSON, a citizen of France, importer, residing at #738 Bloomfield Avenue, Outremont, Quebec, Dominion of Canada, have invented certain new and useful Improvements in Scrubbing Gloves; and I do hereby declare that the following is a full, clear, and exact description of the same.

10 The present invention relates to improvements in a scrubbing glove or mitten which consists in providing the glove with a plurality of transverse ribs on the back of the finger portion and on the palm, so that when 15 the hand is closed a rough or ribbed surface will be provided.

To better understand the invention reference should be had to the accompanying drawings in which:—

20 Figure 1 is a plan view of the back of a glove according to the invention.

Figure 2 is a similar view to the Figure 1 from the opposite side.

25 Figure 3 is a longitudinal sectional view on line 3—3 of Figure 1.

Figure 4 is a perspective view of the glove adapted on a closed hand.

Like numerals of reference indicate corresponding parts in each figure.

30 Referring to the drawings 1 illustrates a

mitt, preferably made of a strong fabric, and having on the outer side of the back, adjacent the finger portion, a plurality of parallel cross ribs 2, consisting of cords 3, covered by a sheet of material and secured 35 by the seams 4 between each of said ribs 2.

On the palm portion of the mitten are provided a plurality of ribs 5 similar in construction to the ribs 2, said ribs being disposed so that when the hand is closed, they 40 will practically form a continuation of the ribs 2, thus offering a "corrugated" surface that will serve the same purpose as a washboard. The ribs 2 and 5 could be made in many other ways, without departing from 45 the spirit and scope of the invention.

What I claim as my invention is:—

A scrubbing mitten of the character described, consisting of a scrubbing surface on the back and palm of the mitten composed 50 of a plurality of parallelly disposed cross-wise lengths of cord suitably secured, substantially as described.

Signed at Montreal, Quebec, Canada, this twenty-eighth day of August, 1920.

AUGUSTE EDOUARD PINSON.
